(57) **CLAIM**

The ornamental design for a board cutter, as shown and
described.

DESCRIPTION

FIG. 1 is a perspective view of a board cutter;
FIG. 2 is a front view of the board cutter of FIG. 1;
FIG. 3 is a back view of the board cutter of FIG. 1;
FIG. 4 is a top view of the board cutter of FIG. 1;
FIG. 5 is a bottom view of the board cutter of FIG. 1;
FIG. 6 is a left elevation view of the board cutter of FIG. 1;
and,
FIG. 7 is a right elevation view of the board cutter of FIG. 1.
The broken lines in the drawings illustrate features of the
board cutter that form no part of the claim.
